UNITED STATES PATENT OFFICE

VINCENT OLIVA, OF NEW YORK, N. Y., ASSIGNOR TO GRAND CENTRAL WICKER SHOP, INC., OF NEW YORK, N. Y., A CORPORATION OF NEW YORK

DESIGN FOR A CHAIR OR THE LIKE

Application filed November 23, 1929. Serial No. 33,533. Term of patent 7 years.

To all whom it may concern:

Be it known that I, VINCENT OLIVA, a citizen of Italy, residing in the city, county, and State of New York, have invented a new, original, and ornamental Design for Chairs or the like, of which the following is a specification, reference being had to the accompanying drawing, forming part thereof.

The figure is a perspective view of a chair showing my new design.

I claim:

The ornamental design for a chair or the like, as shown.

VINCENT OLIVA.
